ACCELERATOR PEDAL

John K. Christian, 2300 N. Plum St., Hutchinson, Kans.

Filed June 12, 1961, Ser. No. 65,556

Term of patent 14 years

(Cl. D14—6)

FIG. 1 is a top plan view of an accelerator pedal, showing my new design.

FIG. 2 is a bottom plan view thereof;

FIG. 3 is a front elevational view thereof;

FIG. 4 is a side elevational view thereof, taken from the left of FIG. 1;

FIG. 5 is a side elevational view thereof, taken from the right of FIG. 1;

FIG. 6 is a cross-sectional view thereof taken on line 6—6 of FIG. 1;

FIG. 7 is a cross-sectional view thereof taken along line 7—7 of FIG. 2; and

FIG. 8 is a cross-sectional view thereof taken along line 8—8 of FIG. 2.

I claim:

The ornamental design for an accelerator pedal, as shown.
